UNITED STATES PATENT OFFICE

160,389

BRASSIÈRE OR SIMILAR ARTICLE

Molly Hollander, New York, N. Y.

Application August 27, 1949, Serial No. 4,718

Term of patent 3½ years

(Cl. D20—4)

To all whom it may concern:

Be it known that I, Molly Hollander, a citizen of the United States of America, residing in New York, county of Bronx and State of New York, have invented a new, original, and ornamental Design for a Brassière or Similar Article, of which the following is a specification, reference being had to the accompanying drawing, forming part thereof.

Fig. 1 is a front view of a brassière or similar article showing my new design.

Fig. 2 is a rear view thereof.

I claim:

The ornamental design for a brassière or similar article, substantially as shown.

MOLLY HOLLANDER.
